FOREIGN PATENT DOCUMENTS

WO 2013019802 2/2013

Primary Examiner — Stacia A Cadmus

(57) **CLAIM**

I claim the ornamental design for a protective wheel spray shield, as shown and described.

DESCRIPTION

FIG. 1 is a front view of the protective wheel spray shield.

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a rear perspective view thereof; and,

FIG. 8 is a front perspective view of the wheel spray shield in its position of use.

In the drawings the broken lines depict environmental subject matter and form no part of the claimed design.

1 Claim, 4 Drawing Sheets
